UNITED STATES PATENT OFFICE.

EDWIN F. MILLER, OF MERCHANTVILLE, NEW JERSEY, AND WILLIAM STEELL JACKSON, OF BALA, PENNSYLVANIA, ASSIGNEES, BY MESNE ASSIGNMENTS, TO UNITED STATES CAST IRON PIPE & FOUNDRY COMPANY, OF BURLINGTON, NEW JERSEY, A CORPORATION OF NEW JERSEY.

COAL FEEDER FOR GAS PRODUCERS AND THE LIKE.

Application filed July 25, 1919. Serial No. 313,929.

To all whom it may concern:

Be it known that we, EDWIN F. MILLER and WILLIAM STEELL JACKSON, citizens of the United States, residing at Merchantville, 5 Camden County, New Jersey, and Bala, Montgomery County, Pennsylvania, respectively, have invented jointly a certain new and useful Coal Feeder for Gas Producers and the like, of which the following is a 10 specification.

Our invention relates to feeders for gas producers, kilns, furnaces and the like in which a charge of material, usually fuel and therefore here so considered, is inserted at 15 the same time that the top of the producer or the like is sealed against escape of gas.

The purpose of our invention is to prevent 20 stoppage of flow of fuel to be fed by permitting a constant flow of fuel less than the amount required and to intermittently increase the fuel flow to provide the desired quantity for the fuel feed.

A further purpose is to provide for a 25 preferably uniform rate of rotation of a sealing spider and to vary the extent of feed by the extent to which a fuel-submerged cut-off is lowered.

A further purpose is to water-cool a feeding rotor which is adapted to turn upon a 30 horizontal axis.

A further purpose is to supply fuel to a gas producer continuously, dropping it from above over a dam and into a rotor, controlling the rate of feed by the height of a dam 35 or breaker in the path of fuel flow.

Further purposes will appear in the specification and in the claims.

We have preferred to illustrate our invention by but one general form, selecting there- 40 for a form which is practical, efficient and thoroughly reliable and which at the same time well illustrates the principles of our invention.

Figure 1 is a vertical transverse section 45 thru the center of a spider feed showing our invention.

Figure 1^a is a vertical section correspond- 50 ing to Figure 1 except for a difference in position of the rotor vanes and the dam and the water cooling of the vanes.

Figure 2 is a vertical longitudinal section 55 thru the center corresponding to line 2-2 of Figure 1.

Figure 3 is a broken longitudinal section of the modification seen in Figure 1^a, having 55 the vanes hollow and water-cooled.

Figure 4 is a section on line 4-4 of Figure 3.

Figure 5 is a side elevation right-side-left to Figure 1 showing the operating parts seen 60 therein in the position of Figure 1.

In the drawings similar numerals indicate like parts.

In feeding fuel thru various automatic forms of compartment feeders of whatever 65 type considerable trouble has been experienced in keeping the fuel moving. Where but a small quantity of fuel lies back of the feed and is replenished frequently by hand, depending upon the feeding mechanism for 70 the regularity and control of the quantity of fuel fed there is little trouble; but where any considerable fuel supply is furnished and attempt is made to obtain full benefit of the automatic character of the feed, the 75 fuel not infrequently clogs or stops and must be loosened by a bar or other implement.

We have discovered that this difficulty can be relieved by permitting a continuous 80 flow of fuel, which has a tendency to keep the fuel moving but which is not sufficient to furnish the entire quantity of fuel intended to be fed, and intermittently increasing the flow for a short time only for the double purpose of making up the difference in quantity of fuel fed and starting the fuel in case of stoppage of the regular flow provided for.

Either the maintained flow or this special 85 flow, preferably the latter, should be made adjustable to suit differing needs of the gas producer. The functions sought can best be accomplished by a dam or breaker over which the fuel is intended normally to flow and which is lowered for a short time at intervals to increase the quantity of fuel fed 95 in proportion to the needs of the producer.

We much prefer to have the fuel flow continuously because the extent of additional opening as well as the time during which there is additional opening may thus both be 100 reduced. The stream of fuel and dam are desirably somewhat shorter axially of the feed rotor than the length of the rotor compartment or compartments and may be made much shorter.

Supplying a rotor adapted to receive the 104

maximum quantity of fuel required we maintain constant speed of rotation of the feeding and sealing rotor and vary the quantity fed by variation in the extent of filling of the compartment or compartments of the feed.

For the purpose of securing greater compactness and reducing the space required for the feeder and connections we supply the fuel to the rotor at the top, controlling the extent of flow by a dam or breaker whose maximum projection is desirably constant and which is dropped to varying positions depending upon the extent of sudden flow which is to be permitted. This principle is applied to a rotor preferably turning upon a horizontal axis and which is most desirably of spider form.

We believe it to be new also to directly water-cool a rotor operating about a horizontal axis, also to use it with water-cooled cooperating sealing surfaces so that the fuel in such a rotor is supported at all times upon water-cooled surfaces.

Though we have shown drawings disclosing the best form of our invention known to us, complying with the statute, these are for purposes of illustration only and will now be described.

The base 10 of the frame 11 is adapted to rest upon the top of any gas producer, kiln, furnace or other such structure and carries its arcuate side-sealing members 13 and 14 to cooperate with a rotor 15.

The arcuate construction is indicated as open at the ends, at which however, the material of the frame is extended circumferentially to form annular seals for the ends of the spider or drum throughout the complete circumference. They also form bearings 16 for the support of the spider or drum ends 17-17'.

A simple form of centering for the spider or drum to prevent longitudinal displacement thereof is shown in the grooves 18, 18' and the pins 19 preferably screwed to place and best seen in Figure 2.

The water supply for the arcuate water chambers 20, 20' may be furnished thru inlet and outlet pipes indicated at 21, 22.

The bearing of the drum heads is advantageous in simplifying the construction, reducing the parts to be finished and utilizing the engagement previously sought at the ends for sealing purposes as a means of support for the spider or drum.

The spider or drum may be driven by a ratchet wheel 23 and connections as is well known in the art, and this wheel may be mounted upon the head 17. In the illustration the body of the rotor is secured to the heads by a shaft 24.

The rotor 15 or 15' is preferably water-cooled and this may be accomplished by forming water spaces 25 within the blades

26 thereof, and supplying water to these thru hollow shaft ends 27 by means of sealing connections 28 without interfering with any parts mounted upon or to be mounted upon the hubs of the rotor heads.

As thus indicated not only the sealing surfaces of the casing but the surfaces of the rotor itself are water-cooled, completely protecting against excessive temperature of the fuel and the consequent stoppage from coking the tar.

The advantages which we thus secure are independent of the character of seal between the vanes of the spider or the surface of the drum, as the case may be, and the adjacent casing. We show slots 29 which have a sealing function because of the accumulation of dust and dirt therein. However, there is not the same need of any of these constructions as in other rotary feeders because of the reduction in expansion of the parts effected by water-cooling, maintaining the spider or drum in substantially its initial diameter and length.

Whether intermittent rotation of the spider or drum be the same at all times as planned or be capable of variation as is permissible or the rotation be continuous (uniform or variable), it is desirable to keep the fuel moving toward the compartments of the spider. To accomplish this we use a sloping inlet 30, whose bottom 31 is steeper than the angle of repose of the fuel upon such a surface. The fuel column will flow in its upper surface 9 at a slightly steeper angle than the angle of repose to which it would come when flow is stopped. This upper surface is maintained free by forming the upper wall 32 of the channel within which it flows higher at the section in question as at 33 than the normal upper surface of the flowing column.

This construction provides a gravity fuel supply inlet in which the upper surface of the fuel is constantly free and in which the amount of slope of this free upper surface will vary slightly according to whether the fuel is flowing rapidly or slowly or, as is permissible but not preferred, stopped.

Access to the inlet is provided by a cover 34, shown as hinged at 35 in an ear secured to the inlet or adjoining structure.

In order to greatly reduce the flow of fuel during most of the movement of the spider, we provide a movable dam or breaker 36, shorter than the length of the rotor so that, with a reasonable size of spider, the flow during the "dipping" of the dam will not unduly fill the compartment of the spider, and supported in arms 37 to swing about shaft 38. It has no crushing function but serves only to block the passage way to the extent that it is raised above the plane of surface 31. The dam drops into space 39 when it is "dipped" or depressed.

We lift the dam or breaker from below to the extent desired and find it most convenient to lift it by a cam and lever connection, rocking the shaft 38 by a lever 40 adjustable 5 angularly about shaft 38 by a set screw 40 and having a series of points of openings 41, to any one of which an operating arm or rod 42 may be connected, affording different possible extents of throw. The rod 42 carries 10 a roller 43 for engagement with a suitable cam face 44 upon cam 45. The rod is guided by a yoke 46 which is secured to a supporting strap 47 by bolt 48. When the bolt is loosened the yoke can be turned about 15 the bolt as an axis so as to accommodate different directions in which the bar must be placed when its upper end coincides with different openings 41. The strap is secured 20 to the frame of the feed at points on opposite sides of the rod.

As the openings lie in a curved line about the guide 46, the highest point of dam or barrier travel will not be affected by connection of the rod with the arm 40 at different 25 leverages, but will remain fixed until reset.

The cam is shaped and timed to suit the size of the compartments and may be shifted or replaced readily.

In the illustration the cam is provided 30 with four like cam surfaces in agreement with the four compartments 49 of the spider, and with intervening peripheral portions of uniform height which are here called dwells 50 and which corresponds to the intended 35 barrier height.

The adjustment of the yoke guide accommodates different points of attachment of the rod along the length of lever arm 40 without objectionably affecting the cooperation 40 of the roller with the cam.

In the case of a drum, the cam will carry but a single cam surface and a much longer uninterrupted dwell.

In this case also the normal height of the 45 barrier will more nearly cut-off the entire flow of fuel and relatively a greater percentage of the total flow should take place during the dip of the dam or barrier than in the use of a dam with the spider form. It will be evident that the same construction with a 50 sufficiently long barrier surface may be adjusted with either form to cut off any percentage or all of the fuel flow in the normal high position of the breaker.

55 The surface of the dam or breaker is desirably a part of the surface of a cylinder in close engagement with the lower edge 31' of the surface 31 and the space 39 should be open at the lower limit to avoid blocking by dust and dirt. The breaker may be made wide enough (circumferentially) to effectively close the passage in fully raised position (as at top in Figure 1) and can be lifted 60 when the device is not in use and be held in

raised position by any suitable fastening, to 65 completely block all fuel flow.

During normal operation it is preferred to have the fuel flow over the top of the dam moderately, in some such position of the parts as shown in Figure 1^a, at a rate too low 70 to supply the desired quantity of fuel for the producer but with the object of keeping part at least of the fuel supply in movement and avoiding stagnation or blocking of the flow. (See dotted intermediate position.) 75 The upper surface of the fuel will lie at an angle approximating its angle of repose as seen at 9, Figure 1^a. By reason of the space between its upper limit and the top of the inlet at this point, lifting of the barrier or 80 dam will not crowd the fuel against the top and cannot jam.

The fuel which falls over the top of the dam will strike the arc of movement of the spider or drum at some such point as 51, falling 85 into the compartment which is then open.

As soon as the trailing blade of this compartment passes this point, fuel entry is cut off from this pocket and the fuel falls into 90 the next pocket following, avoiding the accidental catching of the fuel between this trailing edge and the sealing edge 52. As the dam is dropped the point at which fuel falls into the compartment is moved still 95 farther to the left in Figure 1.

There will be a continual moderate flow of fuel over the top edge of the dam or breaker into the compartment directly beneath the dam while the dam is up (not usually as 100 high as at top in dotted lines) but of less extent than the requirement for the furnace even under minimum supply.

When the cam roller 43 is free to drop to the position shown in Figure 1, the 105 weight of the moving parts of the dam, deliberately over-weighted if necessary, overcomes the frictional resistance of the coal bearing against it and the dam drops to a position which may be designed to be as 110 low as shown in Figure 1, or to lie at any intermediate position, allowing a greater rate of flow of fuel into the compartment during the short time the dam is depressed.

The compartments of the spider or the 115 capacity of the drum are made large enough to hold the maximum flow of fuel past the dam with a maximum depression of the dam for the full estimated length of time, readily accommodating all intermediate 120 rates of fuel feed without necessity for speeding up the spider or drum, though permitting this additional means of taking care of increased fuel flow without undue filling of the compartments.

The cam is designed in depth and angular extent to provide just the rate and time of additional fuel flow and range of adjust-

ment (by set screw and change of lever arm) desirable to relieve any stagnation which may have occurred in the normal rate of flow over the dam and to provide the variations of fuel feed adapted to different producer needs. The external form of cam shown is preferred by us to a cam groove or other positively double-acting cam because of the simplicity of the single-acting form and in view of the fact that the weight of the dam parts may ordinarily be made sufficient to cause reliable downward movement without becoming itself objectionable.

Having thus described our invention, what we claim as new and desire to secure by Letters Patent is:—

1. A feeding rotor adapted to turn about a horizontal axis and having water-cooled fuel-supporting rotor vanes movable with the rotor and providing fuel-carrying pockets between them, in combination with water supply and exhaust through the rotor shaft for the water.
2. A rotor for fuel feeding adapted to rotate about a horizontal axis and having a water-cooled rotor surface supporting the fuel in combination with a water-cooled sealing surface cooperating therewith and water supply for cooling the same.
3. A rotor for fuel feeding adapted to rotate about a horizontal axis and having a water-cooled rotor surface supporting the fuel in combination with a water-cooled sealing surface against which the fuel rests during rotation of the rotor.
4. A feeding rotor for gas producers, in combination with a gravity fuel inlet having the upper surface of the fuel free and means beneath the free surface for interrupting the flow to varying extents, providing a continuous flow of different depths.
5. In a feeder for gas producers, a feeding rotor adapted to turn on a horizontal axis in combination with a gravity fuel inlet providing a free upper surface for the fuel, a movable dam for the fuel supply located beneath the free surface and automatic means for varying the height of the dam during the rotation of the rotor.
6. In a feeder for gas producers, a feeding rotor adapted to turn on a horizontal axis in combination with a gravity fuel inlet providing a free upper surface for the fuel, a movable dam for the fuel supply located beneath the free surface and automatic means for varying the height of the dam during the rotation of the rotor, timed with respect to movement of the rotor.
7. In a feeder for gas producers, a feeding rotor adapted to turn on a horizontal axis in combination with an inlet providing sloping gravity fuel supply therefor, a dam for the supply movable across the fuel column from beneath and shifting mechanism for the dam, timed to the movement of

the rotor and varying its height with different rotor positions.

8. In a gas producer feeder, an automatic sealing feed in combination with an inlet providing sloping gravity fuel supply therefor, a barrier movable into and out of but not completely through the path of movement of the supply to the feed coincidently with the movement of the feed to vary the supply thereto in timing with the feed.

9. In a feeding device for gas producers, an automatic sealing feeder in combination with gravity inlet therefor, providing a free upper surface having a stream of fuel passing therethrough and a barrier movable into and out of the path of flow of the fuel coincidently with movements of the feeder to vary the supply in timing with the feeder.

10. In a feeder for gas producers, a rotor feeder upon a horizontal axis and having an inlet opening, a casing having sealing surfaces therefor, a sloping inlet for furnishing gravity supply of fuel above the feeder, a barrier movable upwardly thru the fuel into the path of travel of the fuel to the rotor and mechanism connected to operate in timed relation with the rotor and adapted automatically to lower the barrier in predetermined relation to the position of the inlet opening.

11. In a feeder for gas producers, a rotor, a casing thereabout providing sealing surfaces therefor and inlet and discharge fuel openings between the sealing surfaces, in combination with a sloping inlet providing a fuel supply for the rotor and a barrier below the fuel surface for checking the passage of said fuel supply to the rotor, occupying different heights below the surface of the column of fuel at different positions of the rotor.

12. In a feeder for gas producers, a feeding rotor, a casing providing sealing surfaces therefor and having top inlet and discharge passages, in combination with gravity fuel feeding devices above the rotor inlet and affording a free upper surface for the fuel feed, and a movable barrier in said feeding devices having its top normally below the angle of repose of the fuel in the supply column.

13. In a feeder for gas producers, a feeding rotor having a horizontal axis, a casing providing sealing surfaces therefor and having top and bottom inlet and discharge passages, in combination with a sloping inlet for furnishing gravity-fuel supply for the rotor, so constituted as to provide a free upper fuel surface, and a barrier in the column of supply, continuously extending to the bottom thereof and lifting means timed with respect to the positions of the rotor to give variant heights to the barrier.

14. In a feeder for gas producers, a rotor

and a casing providing sealing surfaces therefor and having top and bottom inlet and discharge passages, a sloping inlet for furnishing gravity fuel supply for the rotor, so constituted as to provide a free upper fuel surface, in combination with a barrier in the column of supply continuously extending to the bottom thereof and having variant heights at different times, 5
10 timed with respect to the positions of the rotor and at all said heights below the angle of repose of the column of supply fuel.

15. In a feeder for gas producers, a rotor and a casing providing sealing surfaces therefor and having top and bottom inlet and discharge passages, in combination with a sloping inlet providing a column of fuel supply for the rotor so constituted as to provide a free upper fuel surface lying 15
20 at the angle of repose of the material handled, and adapted to flow normally into the rotor at a rate less than the average feed thru the rotor.

25. In a feeder for gas producers, a rotor and a casing providing sealing surfaces therefor and having top and bottom inlet and discharge passages, in combination with a sloping inlet providing a column of fuel supply for the rotor so constituted as 30
35 to provide a free upper fuel surface lying at the angle of repose of the material handled, adapted to flow normally into the rotor at a rate less than the capacity of the rotor and means for intermittently increasing the rate of flow.

40. In a feeder for gas producers, a spider or drum and a casing providing sealing surfaces therefor and having top and bottom inlet and discharge passages, in combination with a sloping inlet providing a column of fuel supply for the spider or drum having a free upper surface lying 45
50 at the angle of repose of the material handled, adapted to flow normally into the spider or drum at a rate less than its capacity, a barrier in the path of movement of the supply extending to the bottom thereof and normally maintained below the surface of the supply, and means for dipping the barrier intermittently to increase the flow.

55. In a feeder for gas producers, a spider or drum and a casing providing sealing surfaces therefor and having top and bottom inlet and discharge passages, in combination with provisions for a column of fuel supply for the spider or drum so constituted as to provide a free upper fuel surface lying at the angle of repose of the column of supply fuel, a barrier in the column normally below its surface and cam actuation for shifting the height of the barrier.

60. In a feeder for gas producers, a sloping inlet for furnishing gravity supply so

constituted as to provide a free upper fuel surface, a barrier normally below the surface of said supply, movable from below into and out of the line of travel of said supply, a gas-sealing feed for the fuel so fed and automatic means, timed with respect to the passage of fuel thru said sealing feed, determining the time and extent of movement of said barrier.

20. In a feeder for gas producers and the like, a sloping inlet for furnishing gravity supply so constituted as to provide a free upper fuel surface, a barrier movable from below into and out of the line of travel of said supply, a gas-sealing feeder for the fuel so fed, automatic means timed with respect to the passage of the fuel thru said seal determining the time and extent of movement of said barrier and an adjustment for the maximum height of said barrier.

21. A rotary fuel feeder for gas producers in combination with a fuel inlet having a sloping bottom and providing free upper surface of the fuel flowing therethrough, a movable barrier movable perpendicularly to the line of fuel flow and automatic means for varying the barrier position during rotation of the feed.

22. The method of controlling the quantity of fuel fed by gravity for a gas producer which consists in damming the bulk of the fuel while permitting continued flow of fuel and varying the height of the column dammed intermittently at regular intervals during the feeding operation.

23. The method of controlling the rate of feed thru a sealing gas producer feeder which consists in retarding it to varying extents and intermittently controlling the supply of said fuel from below across the thickness of the column during the flow of fuel to provide continual supply thereto at successively repeated variant rates.

24. The method of controlling the rate of gravity flow of fuel to a sealing feeder of a gas producer which consists in providing a sloping column of fuel having a free upper surface and interrupting flow of fuel from the bottom to extents varying with the positions of the feeder parts while permitting continued flow of fuel along the upper surface of the column.

25. The method of controlling the rate of fuel fed to a gas producer through a sealing feed device which consists in providing a constant path for part of a gravity column of fuel near the surface and passing over a retarding barrier and intermittently increasing and decreasing the cross section of the path to provide for variation of the flow with a greater depth of column flowing by altering the position of the barrier.

26. The method of controlling the rate of fuel fed to a gas producer thru a sealing

6
feeder which consists in providing a constant path for the upper part of the gravity-flow column and an intermittent sudden enlarged path for a larger depth of flow, timed with reference to the movements of the sealing feeder.

27. The method of controlling the quantity of fuel fed to a gas producer horizontally-rotatable sealing feeder which consists in overflowing the fuel directly above

the compartment of the feeder being supplied, at a point in the rotation of said feeder back of the sealing edge to avoid catching and crushing the falling fuel between the rotor and the sealing edge and increasing the rate of flow at the same time that the mean path of flow is shifted farther from the sealing edge. 15
